UNITED STATES PATENT OFFICE.

STEPHEN H. BROOKS, OF CLEVELAND, OHIO.

SELF-RENEWING FUSE.

1,416,258.

Specification of Letters Patent. Patented May 16, 1922.

Application filed August 11, 1919. Serial No. 316,652.

To all whom it may concern:

Be it known that STEPHEN H. BROOKS, a citizen of the United States, residing at Cleveland, in the county of Cuyahoga and State of Ohio, Plain Dealer Building, has invented certain new and useful Improvements in Self-Renewing Fuses; and he does declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to fuses, the primary object thereof, being to provide a fuse which will be effective to automatically break the circuit when the current above a determined value is passing through the circuit in which the fuse forms a part, and to so construct the fuse that the element which renders certain contacts ineffective, will displace itself in such a manner as to render other contacts effective.

According to my invention the fuse primarily contemplates a plurality of contacts, two or more of which may be normally rendered effective by the interposition of a conductor connector, the device being so constructed that, should the current exceed an estimated value, the conductor-connector will become fused, so as to interrupt the current, but the fused material will displace itself so as to connect other contacts of the same device and which are adapted to be immediately put in circuit with the mean-conductor without any special attention on the part of an operator.

In the drawings:

Fig. I is a perspective view of a fuse constructed in accordance with my invention.

Fig. II is a perspective view of a fuse showing the conductor-connector in its normal position and one-half of the split casing removed.

Fig. III is a similar view showing the conductor-connector after it has been fused to break certain of the contacts, and connect certain other contacts.

Fig. IV is a view similar to Fig. II, showing a slightly modified form of fuse.

The form of fuse shown in Fig. I, II, and III, consists of a casing, which for con-

venience may comprise two parts, 1 and 2, adapted to be connected together by suitable fastening devices 4. The parts 1 and 2 may consist of blocks of insulating material of fiber, porcelain or the like and within the chamber are shown four contacts 5, 6, 7, and 8, from each of which projects a plug or binding post, those illustrated being designated; 5', 6', 7', and 8' respectively, and by reference to Fig. II it will be observed that the contacts 5 to 8 both inclusive are spaced equi-distantly, and that the flat sides of the casing are in vertical planes, so that a conductor-connector, for example, a wafer 9 of fusible material placed within the chamber 3, will rest in a vertical plane with three edges abutting against three of the contacts, in the present instance, 5, 6, and 7. It will be observed that the wafer is to one side of chamber 3, so as to provide a flow space to permit a displacement of the fused connector when an abnormal current flows through the contacts. Assuming that the current is entering the fuse through 5, the line may be tapped through 6 or 7 or both. In the event that abnormal current flows through the conductor-connector, it will become fused and the fused material will pass away from 5 as indicated in Fig. III so that while the current will be broken, the fused-material will connect contacts 6, 7, and 8, and by turning the fuse casing a quarter of a turn, 6 may be connected to the main line and 7 or 8 or both may be connected to leads. Then in the event that abnormal current passes through the circuit, the wafer 9 will again become fused, and break contact with 6 but restore contact with 5, 7, and 8. Therefore, it will be apparent that although the current will be interrupted after an abnormal current passes through the line and through the fuse, the fuse is instantly ready for use without any special treatment.

In Fig. IV, I have shown the casing as substantially triangular with three contacts designating 10, 11, and 12, with corresponding binding posts and projections and the chamber 13 corresponding to 3 in Fig. II, is shown as hexagonal with a conductor-connector 14, connecting the contacts 10 and 12. After abnormal current passes through the line, the conductor-connector 14 will be fused and flow into contact with 11, breaking contact with 10, therefore the conductor which

has previously been connected to 10 may be transferred to 11, the fuse turned one-third of a circle, and the current may then be switched onto the line.

5 I claim—

A renewable fuse comprising a casing having a chamber, contacts equi-distantly spaced

about the perimeter of the chamber, and a gravitating fusible contact connector within the chamber disposed to flow upon fusing so 10 as to connect contacts crosswise of the chamber.

In testimony whereof I affix my signature.
STEPHEN H. BROOKS.
